DESIGN FOR AN AIR VALVE CASING

Eugene J. Lux, New York, N. Y., assignor to Detroit Lubricator Company, Detroit, Mich., a corporation of Michigan

Application December 20, 1937, Serial No. 73,772

Term of patent 14 years

To all whom it may concern:

Be it known that I, Eugene J. Lux, a citizen of Austria and residing in the city of New York, county of New York and State of New York, have invented a new, original, and ornamental Design for an Air Valve Casing, of which the following is a specification, reference being had to the accompanying drawing, forming part thereof.

Figure 1 is a view in perspective of an air valve casing showing my new design;

Fig. 2 is a top plan view of the casing;
Fig. 3 is a view in side elevation thereof, and
Fig. 4 is a view in front elevation thereof.

I claim:
The ornamental design for an air valve casing substantially as shown.

EUGENE J. LUX.
